(57) **CLAIM**

The ornamental design for a food container cover with seal as shown and described.

DESCRIPTION

FIG. 1 is a perspective view taken from the top, front and right side of the food container cover with seal.

FIG. 2 is a front elevation view thereof.

FIG. 3 is a left side elevation view thereof.

FIG. 4 is a back elevation view thereof.

FIG. 5 is a right side elevation view thereof.

FIG. 6 is a top plan view thereof.

FIG. 7 is a bottom plan view thereof.

FIG. 8 is a perspective view showing the bottom, back, and right side thereof.

FIG. 9 is a sectional view along lines 9-9 of the mid-line of FIG. 6; and,

FIG. 10 is an enlarged view taken from within portion "10" on FIG. 9.

(Continued)

The evenly broken lines represent the designation of an enlargement view and form no part of the claimed design.

1 Claim, 6 Drawing Sheets
